FIG. 1 is an isometric view from the front and to one side of the new design;

FIG. 2 is an isometric view from the rear and to one side thereof;

FIG. 3 is a right side elevational view thereof, the left side being a mirror image thereof;

FIG. 4 is a front elevational view thereof;

FIG. 5 is a rear elevational view thereof;

FIG. 6 is a top plan view thereof; and,

FIG. 7 is a bottom plan view thereof.

The portion of the kite shown in broken lines in all views is for illustrative purposes only and forms no part of the claimed design.
